CHRETIAN DORFLINGER, OF TEXAS, PENNSYLVANIA.

Design No. 4,217, dated July 12, 1870.

DESIGN FOR A GLASS LAMP-SHADE.

The Schedule referred to in these Letters Patent and making part of the same

I, CHRETIAN DORFLINGER, of Texas, in the county of Wayne and State of Pennsylvania, have invented and produced a new and original Design for a Glass Lamp-Shade, of which the following is a specification.

My design consists, first, in imparting to a glass lamp-shade an outward form or configuration such as is produced and presented by the union, base to base, of two conical frustums of different heights and inclinations, the lower inverted frustum being shorter and more acutely inclined than the upper, and provided about the opening therein with a rim to fit upon the holder of the lamp or burner upon which it is to be placed; the nature of my said design being fully represented in Figure 1 of the accompanying drawing.

It consists, in the second place, in imparting an outward roll or curve to the upper rim of the upper part of a shade, having otherwise the form and outward configuration above described, to impart thereto a

more complete and graceful outline; the nature thereof being fully represented in Figure 2 of the accompanying drawing.

The plain glass lamp-shade, of the design hereinbefore described, may be ornamented at pleasure by grinding, etching, staining, or otherwise, as good taste may suggest.

I claim as my invention—

The design for the outward form or configuration of a glass lamp-shade, as represented in fig. 1 of the accompanying drawing.

Also, the combination of an outward curve or roll, with the upper rim of a lamp-shade, having otherwise the form represented in fig. 1, as is illustrated in fig. 2 of the accompanying drawing.

CHRETIAN DORFLINGER.
